UNITED STATES PATENT OFFICE

PHILIP MASON CABELL, OF NEW YORK, N. Y.

APPARATUS FOR GASIFYING LIQUID FUEL

Application filed August 5, 1924, Serial No. 730,324. Renewed June 4, 1931.

This invention relates to apparatus for gasifying liquid fuel. The invention embodies improvements on the apparatus shown in my application Serial No. 652,011, filed 5 July 17, 1923, and the apparatus of the present invention is intended especially for practicing the method disclosed in my said earlier application, although features of the present invention may be found useful for other purposes.

An object of the invention is to provide an improved apparatus for converting liquid fuel into permanent gas in accordance with the method of my said earlier application 15 and to provide an apparatus which shall be highly efficient in operation and shall be of relatively simple and economical construction and such that the interior parts thereof shall be readily accessible as for inspection 20 or renewal.

The invention comprises structural improvements in the converter casing, improved means for supporting the superposed spaced permeable beds of refractory material within 25 the converting chamber, and means for securing a better distribution of the oil or other liquid fuel entering the converting chamber. The invention also comprises other features, all of which will be fully disclosed 30 and specifically pointed out in the claims.

As a full understanding of the invention can best be given by a detailed description of an approved construction embodying the various features of the invention in connection 35 with drawings illustrating such an approved embodiment, such a description will now be given in connection with the accompanying drawings; in which:—

Fig. 1 is a central sectional elevation of the converter taken on line 1—1 of Fig. 3;

Fig. 2 is a central sectional view of the upper part of the converter taken on line 2—2 of Fig. 3, in a plane at right angles to the sectional plane of Fig. 1;

Fig. 3 is a top plan view of the converter;

Fig. 4 is a horizontal sectional view taken on line 4—4 of Fig. 2;

Fig. 5 is a plan view of one of the trays for supporting a bed of refractory material;

Fig. 6 is a sectional view of the tray shown

in Fig. 5 taken on line 6—6 of Fig. 5, on a larger scale;

Fig. 7 is a detailed sectional view taken on line 7—7 of Fig. 5;

Fig. 8 is a horizontal sectional view of the cap piece taken on line 8—8 of Fig. 1, on a larger scale;

Fig. 9 is a fragmentary horizontal sectional view taken on line 9—9 of Fig. 1 on a plane extending through the throat of the Venturi inlet tube; and

Fig. 10 is a top plan view of the fuel distributor.

Referring to the drawings, the converter as shown is of vertical cylindrical form having 65 a cylindrical insulating outer casing, a cylindrical pot within the casing open at the bottom and with its wall spaced from the casing wall, horizontal trays arranged within the pot to carry refractory material forming 70 permeable beds or baffles leaving a tortuous passage for the gases flowing downward through the pot, an inlet opening in the top of the casing through which the oil or other liquid fuel to be gasified enters the pot and 75 also air and steam in controlled quantities, and an outlet for the gas opening from the upper part of the annular space between the casing wall and the pot.

The side walls of the converter casing are 80 formed by an outer shell 10 and an inner shell 11 of sheet metal of relative diameter such as to leave a cylindrical space between them, which space is filled with insulating material 12. The shells 10 and 11 are supported by a bottom casting formed to provide an inner flanged bottom plate 13 forming the bottom of the converting chamber and an annular vertically extending flange 90 or wall 14 spaced from the flange of the bottom plate 13 and connected thereto by webs 15, the bottom of the inner shell 11 being connected to the flange of the bottom plate 13, and the bottom of the shell 10 being connected to the outer flange 14. A plate 16 closes the bottom of the casting and the insulating filling 12 fills the space between the bottom plate 13 and the flange 14 and plate 16. Legs 17 are bolted to the flange 95 14 by bolts extending through vertical slots 100

in the legs to permit of adjustment of the legs if the surface on which the converter is standing is not exactly horizontal. A drain opening is provided in the bottom 5 of the casing from which leads a drain pipe 18 provided with a drain cock 19. An annular casting 20 extending between the shells 10 and 11 forms the top of the side walls and extends inward from the inner shell to provide a support for the pot. 10

A removable top wall or cover rests on and is bolted to the annular casting 20. It comprises a cover casting 25 having an outer vertical flange 26, and a top plate 27 15 which rests on the flange 26 leaving a space between the plate and the cover casting within the flange which is filled with insulating material 12a. The cover casting is formed with a central collar 28 which extends upward about a central opening, the walls of the opening being inclined downwardly and inwardly to form a seat for a nozzle piece 30, the opening through which is in the form of a short Venturi tube which provides the 20 inlet opening through which the air enters the converting chamber. A removable cap 31 is bolted to the collar 28. This cap is formed by a casting having an inner flange 32, by which the cap is supported on the 25 upper edge of the collar 28, and an outer flange 33 which extends down to meet the edge of the plate 27, the space between the flanges being desirably filled with insulating material as shown. Air enters the space 30 within the inner flange 32 from a supply pipe 35 through a passage 36 extending between the cap flanges. The flow of air into the converting chamber is controlled by a shutter valve comprising a fixed shutter plate 37 clamped between the collar 28 and the 35 cap sleeve 32, and a movable shutter plate 38 mounted on a rotatable hollow stem 39 which extends through a central opening in the top of the cap 31 and is provided outside the cap with an operating handle 40.

The gas delivery pipe 41 through which the gas leaves the converting chamber leads to a suction device, which may be an internal combustion engine as shown in my said application Serial No. 652,011. The suction 50 through the pipe 41 produces a sub-atmospheric pressure within the converting chamber and this causes air to be drawn into the chamber through the regulating valve and Venturi inlet 30.

The liquid fuel is supplied from a float chamber 45 through a pipe 46 to an annular passage 47 formed in the body of the Venturi tube 30 and from which a series of orifices 48 open into the throat of the venturi. Because of the reduced pressure and increased flow velocity of the inflowing air as it passes through the throat of the venturi, a suction is created through these inlet orifices whereby 55 the fuel liquid is sucked into the Venturi

throat at a rate proportional to the amount of air passing through the throat. Liquid fuel, such as oil, is supplied to the float chamber 45 through a supply pipe 49 from any suitable source of supply. The fuel level in 70 the float chamber is below the level of the Venturi orifices and the liquid passes through an outlet opening 50 and past an adjustable valve 51 to the intake pipe 46. The valve 51 serves for adjusting the proportionate 75 amount of fuel caused to flow into the converting chamber by the inducing action of the inflowing air.

It is of great importance in securing uniform and most efficient operation of the converter that the liquid fuel which enters the converting chamber through the Venturi inlet shall be well and uniformly distributed as it enters the chamber for securing a better initial vaporization of the liquid fuel and a 80 suitable distribution over the top baffle bed of such of the fuel as reaches such baffle bed before vaporization. For this purpose, I provide at the top of the converting chamber directly beneath the lower, or discharge, end 85 of the Venturi tube and extending outward and downward therefrom a liquid fuel distributing device, and I also form the inner surface of the expanding portion or discharge cone of the Venturi tube so as to direct the fuel entering from each of the inlet orifices 48 to a particular portion or sector of the distributor. I find that the liquid fuel passing through the inlet orifices into the 90 throat of the venturi under the inducing action of the inflowing air is not projected in the form of jets into the air current but rather tends to flow down along the wall of the expanding portion of the venturi. Some of the liquid, the amount depending 95 on the character of the liquid and the flow velocity and pressure reduction of the air stream and the shape of the venturi, may be taken up by the air stream in the Venturi tube, but the greater part flows downward as 100 a liquid. For directing the downwardly flowing liquid I form grooves 55 in the inner surface of the venturi, a groove extending 105 downward from each inlet orifice. These grooves direct the flow of the liquid from each orifice to a particular point of discharge at the lower end of the venturi. From the discharge end of the Venturi tube the liquid fuel falls on to the distributor.

The distributor 56 is formed to provide 110 an upper frusto-conical or outwardly and downwardly inclined distributing surface, the distributor being circular in shape of a diameter substantially less than the diameter of the pot and having a central opening. 115 The distributor is supported, as by rods 57, with its central portion directly beneath and closely adjacent to the discharge end of the Venturi tube and axially aligned therewith, so that the air flowing inward through the 120 125 130

Venturi tube may pass on into the converting chamber through the central opening of the distributor. The upper edge of the distributing surface is of a diameter slightly less than the diameter of the discharge end of the Venturi tube so that liquid fuel falling from the ends of the grooves 55 will fall on the distributing surface. The distributing surface is divided by radial ribs 58 into a plurality of equal sectors, one to receive the liquid from each of the grooves 55. For the purpose of causing the liquid falling on each sector of the distributing surface to be distributed over the surface of the sector as it flows outward thereon, each sector is formed at its inner upper end with a depression *a* and beyond this depression the surface is divided by radial grooves *b* into a plurality, three as shown, of equal flow-ways. These grooves *b* extend for a short distance, each ending in a slight depression, and beyond each groove *b* the portion of the distributing surface extending radially therefrom is divided by grooves *c* into a plurality, three as shown, of radial flow-ways, each of which receives a portion of the liquid from the flow-way *b*. The liquid falling from each of the Venturi grooves 55 on to one of the sectors of the distributing surface will, therefore, as it flows downward be distributed to the several grooves or flow-ways *c*. The flow-ways *c* are of varying length, terminating at varying distances from the axis of the distributor so that liquid will fall from the distributor at varying distances from the axis thereof. Holes 59 are also provided extending through the distributor for discharging liquid in a zone or area within that in which the liquid from the ends of the shortest flow-ways *c* is discharged.

The distributor may be made of metal or other suitable material and is most desirably made with a relatively thin wall so as to provide beneath it a flaring space for the discharge of the air from the Venturi tube and to give as much free space for distribution of the air and steam beneath the distributor as possible.

The pot or inner casing 60 within which the baffling beds of refractory materials are supported, is hung from the top annular casting 20, and may be formed of sheet metal or otherwise formed of suitable metal or other suitable material and has an outwardly extending flange 61 at its upper edge which lies on the upper surface of the casting 20 and is clamped between such surface and the cover casting 25. A gasket 62 is also provided between the annular casting 20 and the cover casting in order to insure a gas-tight joint. The inner casing or pot is open at its lower end except for a narrow inwardly extending supporting flange 63 and extends down to within a short distance of the bottom plate

The permeable baffle 65, formed most desirably of layers or beds of broken porous and absorbent refractory material, are supported on trays 66 and 67 having foraminous bottoms which may be formed of netting of suitable metal. It is desirable in order to permit renewal of the broken refractory material in the trays, and renewal of the trays themselves when necessary, that the pot may be readily removed from the converting chamber and that the trays shall be separately removable. The pot in the construction shown is readily removable by simply lifting it out when the top wall of the converter casing has been removed. The trays are so formed in units that the bottom one rests on the flange 63 at the bottom of the pot and each successive tray rests upon and is supported by the one beneath it. Each tray unit comprises an outer annular wall 70 and an annular flange piece 71 which fits within the upper edge of and is riveted or otherwise secured to the wall 70, and which extends above the upper edge of the wall 70. The foraminous bottom 72 is supported from the wall 70 by means of parallel tubular bars 73 and short tubular bars 74. The bars 73 are secured to the wall 70 by means of pins 75 which extend through the wall and into the ends of the bars. The bars 74 extend each from one of the bars 73 to the wall 70 and each is connected to the wall 70 by a pin 75 extending through the wall and into the bar, and to its bar 73 by means of a pin 76 extending into the bar and having its outer end formed in a hook or eye extending about the bar 73. The annular walls 70 of the several trays are of the same diameter and of such diameter as to fit freely within the pot 60. The wall of the bottom tray rests on the supporting flange 63. The bottom of the wall 70 of the next tray rests on the top of the wall 70 of the bottom tray with the flange 71 of the bottom tray extending up within it, thereby holding the two trays securely in alignment. Successive trays are supported in the same manner each on the one next below, and a slightly flaring annular deflecting wall 77 is provided to rest on the top of the wall 70 of the uppermost tray and fitting closely against the wall of the pot at its upper edge. This deflecting wall section 77 prevents the passage of gases into the space between the walls 70 and the top wall.

On the uppermost tray 66 and on each alternate tray 66 the refractory material covers the tray except for an unobstructed annular space adjacent the outer wall of the tray, the material being confined and this free space provided by means of an annular vertical wall 78 resting on the tray bottom. On the other alternate trays 67 the refractory material extends clear out to the outer tray wall, but an annular vertical wall 79 of relatively small diameter set centrally on

the tray bottom holds back the refractory material and provides an unobstructed central opening through the bed. There is thus provided a series of permeable baffles so arranged as to leave a free but tortuous flow passage of non-uniform cross-section from the top to the bottom of the converting chamber.

Steam is supplied to the converting chamber from any suitable source through a supply pipe 80 leading to a needle valve 81 mounted on the upper end of the hollow stem 39. From this valve the stem passes through the stem 39 and is discharged into the converting chamber from a nozzle pipe 82. The nozzle pipe extends from the hollow stem 39 down through the Venturi tube, the discharge end of the pipe being desirably somewhat below the lower or discharge end of the Venturi tube. The nozzle pipe is threaded at its upper end and screwed into the lower end of the hollow stem 39 so that it may be readily detached and replaced by one of different external diameter in the part passing through the throat of the venturi, if this is desired for the purpose of changing the effective area of the Venturi throat.

During the operation of the converter a high temperature is maintained in the converting chamber by combustion of a part of the fuel therein. For starting the converter, a preliminary heating means is provided similar to that shown in my said application Serial No. 652,011. Such means is formed to provide a conduit 90 leading in from outside the converter casing to openings in the wall of the pot 60 and in the tray wall 70 between the uppermost tray and the one beneath it, and such means comprises a casting or other metal body or structure 91 set in an opening in the outer casing of the converter and secured to the inner casing wall or shell 11 by screw bolts extending through the shell 11 into a filling block 92 fitted and filling the space between the shell 11 and the wall of the pot 60. The casting 91 is formed to provide an open through passage forming part of the conduit 90 and a registering opening is formed through the inner shell 11 and block 92. The casting is formed with a bottom recess in which is placed a body of absorbent refractory material, or wick, 93 to which liquid fuel is supplied from a cup 94 which receives fuel when desired from a pipe 95 provided with a valve 96. A slide valve 97 is provided for closing or opening the conduit outside the body of absorbent material 93. The valve slides horizontally and is of downwardly tapering form fitting in a downwardly tapering slot formed between the outer end of the casting 91 and a second casting 98. The casting 98 is formed to provide an igniting means and has a passage forming a continuation of the conduit 90, a lamp or small receptacle 99 for holding

a small quantity of liquid fuel, an upwardly directed chimney 100, and a shutter 101 normally closing the extreme outer end of the conduit 90. A check valve 102 is provided within the conduit 90 formed of two plates extending at an angle to each other, the valve being hinged within the conduit in such manner that the outer plate normally extends across the conduit resting against a stop 103, while the inner plate is inclined inwardly. The outer plate has an opening 104 through which the flame from the igniting lamp 99 may be drawn inward. In case of an accidental rise in pressure in the pot, the gas starting to flow out through the conduit 90 swings the valve so as to bring the inner valve plate across the conduit and against the stop 103, thus quickly closing the valve and preventing the outflow of gas and flame through the conduit.

For indicating the temperature of the produced gas as it rises through the space between the outer casing and the pot 60, a pyrometer 105 is provided having a rod 106 extending downward in the space between the casing and the pot. To permit observation of conditions within the pot during the operation of the converter, peep holes 107 and 108 are provided formed by tubes provided with glass closures in the usual manner and extending one through the top or cover wall of the casing to give a view of conditions above the uppermost baffle, and the other through the side wall of the casing for viewing conditions between the uppermost baffle and the one next below.

In starting the converter, the lamp 99 is lighted through the cover 101 which is then closed, and the valve 97 is open. Suction is applied to the gas delivery pipe 41, and the air valve 38 and the fuel valve 51 being closed and the steam shut off, air is drawn into the pot through the conduit 90. This current of air sucks flame from the lamp 99 into the conduit and ignites the fuel in the wick 93, and the relatively large flame from this wick is drawn into the space between the two uppermost baffles. As this upper part of the pot becomes well heated, the air valve 38 and the fuel valve 51 are partly opened and a little steam may be admitted by opening the needle valve 81. The liquid fuel drawn in through the Venturi tube is vaporized and ignited by the flame from the wick 93 and the heating up of the converting chamber then becomes more rapid, and when the temperature within the chamber is sufficient to maintain combustion without requiring the flame from the wick 93 the supply of oil to the wick may be cut off and the slide valve 97 closed. As the temperature increases, more fuel is admitted until the desired or normal rate of supply of fuel is reached, and as the temperature rises the needle valve 81 is also opened so as to admit sufficient steam to prevent

combustion from taking place above the uppermost baffle. During this heating up a greater amount of air may be admitted than is required for maintaining temperature within the pot after the desired operating temperature has been once reached. When the desired operating temperature has been reached, as indicated by the pyrometer, the air valve is set so as to permit only sufficient combustion of the fuel within the chamber to maintain the desired temperature. The production of gas may then be continued for a long period of time. If the suction applied to the gas delivery pipe 41 varies, the amount of fuel and air drawn into the converting chamber will vary correspondingly and substantially proportionately, the amount of gas produced and delivered by the converter depending upon the suction applied to the delivery pipe. This variation may extend over quite wide limits within the capacity of the converter. For best results, the supply of steam to the converting chamber should be adjusted according to variations in the amount of fuel and air entering the converting chamber and the resulting amount of gas produced.

While I do not wish to limit myself to any theory as to the operation of the converter in producing gas, I believe the operation to be as stated in my said application Serial No. 652,011.

The better distribution of the liquid fuel as it enters the converting chamber from the Venturi tube 30 secured by the distributing means of the present invention results in a more efficient operation of the converter under all conditions. The quantity of the evaporating material, that is, the porous absorbent refractory material of the baffles 65, required is reduced, as well as the size and weight of the converter. Such distributing means also has the additional advantage that when the converter is used, as on a boat, for example, where it does not at all times stand vertically, the tendency of any tilting of the converter to cause uneven distribution of the entering fuel, causing it to be delivered mostly to one side or another of the converting chamber, is practically eliminated. Under such conditions, the flow-directing grooves of the Venturi tube insure the desired distribution of the liquid to the distributor, and the distributor delivers the liquid from each of the directing grooves of the Venturi tube to a desired portion of the uppermost baffle, the downward slant of the distributing surface of the distributor being sufficient to cause outward flow of the liquid on all sectors or portions thereof even though the converter be tilted to a considerable angle.

It is apparent that the interior of the converting chamber is readily accessible by merely removing the cover casting 25 and the parts carried thereby. The inner casing or

pot 60 may then be lifted out bodily with its baffle trays, and the baffle trays may be lifted one after the other from the pot either when so removed from the converting chamber or without removing the pot from the converting chamber. Refractory material on the trays may thus be readily renewed when desired or changes made in the amount of refractory material used or the relative arrangement of the trays.

What I claim is:

1. Apparatus for converting liquid fuel into fixed gas, comprising a casing formed to provide a converting chamber, an inlet passage through the top of the casing having the form of a Venturi tube set with its discharge end directed downward, means for causing a current of air to flow through the inlet passage into the converting chamber, means for supplying liquid fuel to the Venturi tube, the surface of the discharge cone of the Venturi tube being formed to direct the flow of liquid downward thereon, and a distributor directly beneath the discharge end of the Venturi tube having a downwardly and outwardly inclined surface provided with flow-directing means for directing the flow of liquid radially outward thereon.

2. Apparatus for converting liquid fuel into fixed gas, comprising a casing formed to provide a converting chamber, an air inlet passage through the top of the casing having the form of a Venturi tube set with its discharge end directed downward and provided with a circumferentially arranged series of fuel inlet openings for supplying liquid fuel to the Venturi tube, the surface of the discharge cone of the Venturi tube being formed to direct the flow of liquid from each said opening downward therefrom, and a distributor directly beneath the discharge end of the Venturi tube to receive the liquid fuel having an outwardly and downwardly inclined distributing surface provided with flow directing means for directing the flow of liquid radially outward thereon.

3. Apparatus for converting liquid fuel into fixed gas, comprising a casing formed to provide a converting chamber, an air inlet passage through the top of the casing having the form of a Venturi tube set with its discharge end directed downward and provided with a circumferentially arranged series of fuel inlet openings for supplying liquid fuel to the Venturi tube, the surface of the discharge cone of the Venturi tube being formed to direct the flow of liquid from each said opening downward thereon, and distributing means for distributing the fuel from each said opening as it drops from the end of the Venturi tube.

4. Apparatus for converting liquid fuel into fixed gas, comprising a casing formed to provide a converting chamber, a fuel distributor at the top of the converting chamber

having an outwardly and downwardly inclined distributing surface divided by radial ribs into sectors, and means for supplying fuel liquid to each sector of the distributing surface, the surface of each sector being formed to cause the liquid flowing outward thereon to spread laterally and to fall therefrom at various distances from the center of the distributor.

10 5. Apparatus for converting liquid fuel into fixed gas, comprising a casing formed to provide a converting chamber, a conical fuel distributor at the top of the converting chamber having an outwardly and downwardly inclined distributing surface formed with a circularly arranged series of depressions and a plurality of grooves extending radially outward from each depression, and means for supplying fuel liquid to each depression.

15

20 6. Apparatus for converting liquid fuel
into fixed gas, comprising a casing formed to
provide a converting chamber, an air inlet
passage through the top of the casing having
the form of a Venturi tube set with its dis-
charge end directed downward and provided
25 with a circumferentially arranged series of
fuel inlet orifices opening to the throat of
the Venturi tube, the surface of the discharge
cone of the Venturi tube being formed with
30 flow-directing grooves leading from said
orifices to the discharge end of the tube, and
a distributor directly beneath the discharge
end of the Venturi tube to receive the fuel
falling from the end of the discharge cone of
35 the Venturi tube, said distributor having a
central opening for the flow of air from the
Venturi tube into the converting chamber
and having an outwardly and downwardly
inclined radially grooved distributing sur-
face.

40 face.

45 7. Apparatus for converting liquid fuel into fixed gas, comprising a casing formed to provide a converting chamber, an air inlet passage through the top of the casing having the form of a Venturi tube set with its discharge end directed downward and provided with a circumferentially arranged series of fuel inlet orifices opening to the throat of the Venturi tube, the surface of the discharge cone of the Venturi tube being formed with flow-directing grooves leading from said orifices to the discharge end of the tube, a distributor directly beneath the discharge end of the Venturi tube to receive the fuel falling from the end of the discharge cone of the Venturi tube, said distributor having a central opening for the flow of air from the Venturi tube into the converting chamber and having an outwardly and downwardly inclined radially grooved distributing surface, and a steam inlet pipe extending into the Venturi tube to discharge steam through the central opening of said distributor.

8. Apparatus for converting liquid fuel
65 into fixed gas, comprising a casing formed to

provide a converting chamber, an air inlet passage through the top of the casing having the form of a Venturi tube set with its discharge end directed downward and provided with a circumferentially arranged series of fuel inlet orifices opening to the throat of the Venturi tube, and a distributor directly beneath the discharge end of the Venturi tube to receive the fuel falling from the end of the discharge cone of the Venturi tube, said distributor having a central opening for the flow of air from the Venturi tube into the converting chamber and having an outwardly and downwardly inclined distributing surface divided by radial ribs into sectors, the surface of each sector being formed to cause the liquid flowing outward thereon to spread laterally and to fall therefrom at various distances from the center of the distributor. 70 75 80

9. Apparatus for converting liquid fuel into fixed gas, comprising a casing formed to provide a converting chamber, an air inlet passage through the top of the casing having the form of a Venturi tube set with its discharge end directed downward and provided with a circumferentially arranged series of fuel inlet orifices opening to the throat of the Venturi tube, and a distributor directly beneath the discharge end of the Venturi tube to receive the fuel falling from the end of the discharge cone of the Venturi tube, said distributor having a central opening for the flow of air from the Venturi tube into the converting chamber and having an outwardly and downwardly inclined distributing surface formed with a circularly arranged series of depressions and a plurality of grooves extending radially outward from each depression. 85 90 95 100

10. Apparatus for converting liquid fuel 105
into fixed gas, comprising a casing formed to
provide a converting chamber, an air inlet
passage through the top of the casing having
the form of a Venturi tube set with its dis- 110
charge end directed downward and provided
with a circumferentially arranged series of
fuel inlet orifices opening to the throat of the
Venturi tube, and a distributor directly 115
beneath the discharge end of the Venturi tube
to receive the fuel falling from the end of
the discharge cone of the Venturi tube, said
distributor having a central opening for the
flow of air from the Venturi tube into the 120
converting chamber and having an outwardly
and downwardly inclined distributing sur- 125
face divided by radial ribs into sectors, the
surface of each sector being formed with a
depressed portion and a plurality of grooves
extending radially outward from the de- 130
pressed portion and providing flow-ways end-
ing and discharging the liquid at various
distances from the center. 135

11. Apparatus for converting liquid fuel into fixed gas, comprising a casing formed to provide a converting chamber, a plurality 130

- of baffles of porous absorbent refractory material arranged within the chamber in superposed spaced relation so as to leave a free tortuous downward flow passage through the 5 chamber, an air inlet passage through the top of the casing having the form of a Venturi tube set with its discharge end directed downward and provided with a plurality of fuel inlet orifices opening to the throat of the 10 Venturi tube, the surface of the discharge cone of the Venturi tube being formed with flow directing grooves leading from said orifices to the discharge end of the tube, and distributing means in the converting chamber 15 directly beneath the discharge end of the Venturi tube to receive the fuel from the ends of said grooves.
12. Apparatus for converting liquid fuel into fixed gas, comprising a casing formed 20 to provide a converting chamber, a plurality of baffles of porous absorbent refractory material arranged within the chamber in superposed spaced relation so as to leave a free tortuous downward flow passage through the 25 chamber, an air inlet passage through the top of the casing having the form of a Venturi tube set with its discharge end directed toward the uppermost baffle, a gas outlet adapted to have suction applied thereto to maintain 30 a sub-atmospheric pressure within the chamber and to draw the gas therefrom, the oil inlet passage being provided with a circumferentially arranged series of fuel inlet orifices opening to the throat of the Venturi 35 tube, a fuel supply conduit communicating with said orifices, the surface of the discharge cone of the Venturi tube being formed with flow directing grooves leading from said fuel orifices to the discharge end of the tube, and 40 a distributor in the converting chamber directly beneath the discharge end of the Venturi tube to receive the fuel from the ends of said grooves.
13. A device for supplying a liquid and a 45 gas, comprising a Venturi tube set with its discharge end directed downward and having a circumferentially arranged series of liquid inlet openings and the surface of the discharge cone of the tube being formed with 50 flow directing grooves leading downward from said openings.
14. A device for supplying a liquid and a gas, comprising a Venturi tube set with its axis vertical and its discharge end downward 55 and having a plurality of liquid inlet orifices opening to the throat of the tube, the surface of the discharge cone of the Venturi tube being formed with flow-directing grooves leading downward from the orifices.
- 60 15. A device for supplying a liquid and a gas, comprising a Venturi tube set with its axis vertical and its discharge end downward and having a plurality of liquid inlet orifices opening to the throat of the Venturi tube and 65 having the surface of its discharge cone formed with flow directing grooves leading downward from the orifices, and a distributor mounted directly below the Venturi tube having a central opening for the flow of gas from the tube and an outwardly and downwardly 70 inclined distributing surface divided by radial ribs into sectors, the surface of each sector being formed with a depressed portion and a plurality of grooves extending radially therefrom.
16. A device for supplying a liquid and a gas, comprising a Venturi tube set with its axis vertical and its discharge end downward and having a plurality of liquid inlet orifices opening to the throat of the Venturi tube and 75 having the surface of its discharge cone formed with flow directing grooves leading downward from the orifices, and a distributor mounted directly below the Venturi tube having a central opening for the flow of gas from the tube and an outwardly and downwardly 80 inclined distributing surface divided by radial ribs into sectors, the surface of each sector being formed to cause the liquid flowing outward thereon to spread laterally and to fall therefrom at various distances from the center of the distributor.
17. A liquid distributor having an outwardly and downwardly inclined distributing surface divided by radial ribs into sectors, the surface of each sector being formed with a depressed portion and a plurality of 85 grooves extending radially therefrom.
18. The combination with a casing formed to provide a heating chamber and having a removable cover, of a removable inner casing open at the bottom hung from the top of the main casing and extending downward within the chamber with its wall spaced from the chamber wall and free at the bottom, a series of foraminous trays removably supported within the inner casing in spaced superposed relation, and separate layers of material arranged to leave unaligned openings past the material on successive trays to 90 provide a tortuous flow passage through the chamber, a fuel inlet at the top, and a gas outlet from the top of the annular space between the inner casing and the outer casing.
19. Apparatus for converting liquid fuel into fixed gas, comprising a casing formed to provide a converting chamber and having a removable cover, a series of individually removable foraminous trays supported within the chamber in spaced superposed relation, and separate layers of broken refractory material on said trays, the trays being provided with means for positioning the refractory material in successive trays to leave unaligned, substantially unobstructed openings to provide a tortuous flow passage through the chamber.
20. Apparatus for converting liquid fuel into fixed gas, comprising an outer casing formed to provide a converting chamber and 100

having a removable cover, a removable inner casing hung within the chamber, a series of individually removable foraminous trays supported within the inner casing in spaced superposed relation and separate layers of broken refractory material on said trays, the trays being provided with means for positioning the refractory material in successive trays to leave unaligned, substantially unobstructed openings to provide a tortuous flow passage through the chamber.

21. Apparatus for converting liquid fuel into fixed gas, comprising an outer case formed to provide a converting chamber and having a removable cover, a removable inner casing open at the bottom hung from the top of the outer casing and extending downward within the chamber with its wall spaced from the chamber wall and free at the bottom, a series of individually removable foraminous trays supported within the inner casing in spaced superposed relation, and separate layers of broken refractory material on said trays, the trays being provided with means for positioning the refractory material to leave unaligned substantially unobstructed openings to provide a tortuous flow passage through the chamber.

22. Apparatus for converting liquid fuel into fixed gas, comprising a casing formed to provide a converting chamber and having a removable cover, a series of trays removably supported within the chamber in spaced superposed relation, each tray having an outer wall and a foraminous bottom, the bottom of the outer wall of each successive tray resting on the top of the outer wall of the tray beneath it, and permeable baffle beds of refractory material on said trays, the trays being provided with means for positioning the refractory material in successive trays so as to leave unaligned, unobstructed openings through the trays to provide a tortuous flow passage through the chamber.

23. Apparatus for converting liquid fuel into fixed gas, comprising an outer casing formed to provide a converting chamber and having a removable cover, an inner casing open at the bottom hung within the chamber with its wall spaced from the chamber wall and removable from the chamber when the cover of the chamber is removed, a series of individually removable trays supported within the inner casing in spaced superposed relation, permeable baffle beds of refractory material on said trays, retaining walls on the trays for positioning the baffling material to leave an unobstructed outer space adjacent the outer wall of alternate trays, and an unobstructed central opening at the center of the other alternate trays, means for supplying liquid fuel and a limited amount of air to the top of the converting chamber, and an outlet for the gas.

24. Apparatus for converting liquid fuel

into fixed gas, comprising a casing formed to provide a converting chamber and having a removable cover, a series of individually removable trays supported within the chamber in spaced superposed relation, each tray having an outer wall and a foraminous bottom supported by tubular bars secured to the tray wall by pins which extend through the wall and into the ends of the bars, the bottom of the outer wall of each successive tray resting on the top of the tray beneath it, permeable baffle beds of refractory material on said trays, walls on the trays for positioning the baffling material to leave unaligned openings past the baffling material on successive trays to provide a tortuous flow passage through the chamber, means for supplying liquid fuel and a limited amount of air to the top of the converting chamber, and an outlet for the gas.

In testimony whereof, I have hereunto set my hand.

PHILIP MASON CABELL.
